TOY WITH TRAVELING FIGURETTE

William R. Smith, Philadelphia, Pa., and Gabriel R. Monaco, New Haven, Conn., assignors to The A. C. Gilbert Company, New Haven, Conn., a corporation of Maryland

Application February 14, 1951, Serial No. 210,813

16 Claims. (Cl. 46—216)

1

This invention relates to toy apparatus in the nature of trackside station as an accessory for toy railroads and involving a platform whereon free moving figurettes representing men, cattle or other living beings are animated in a manner to travel automatically about the platform as well as to move both into and out of a railway car standing on an adjoining stretch of toy railroad track.

A general object of the invention is to impart automatically to such figurettes progressive movement imitative of the natural travel of people or live stock at a passenger station or at a freight station such as a stockyard or corral.

It has long been known that loose or free moving pieces such as toy figurettes can be made to advance along a horizontal floor or support surface by vibrating such surface in various ways. To this end it has been proposed to equip either the base of the figurette or the floor surface with a pilose substance or some equivalent formation of flexible projections upon whose free ends the figurette stands. When subjected to vibration of the support surface on which they rest, such projections yield flexibly to vibratory impulses which take place in a direction that most easily flexes them but yield much less readily or not at all to impulses acting in the opposite direction, namely in a direction head on against their ends. Therefore the pile or shag of a fabric can act as a strut and be produced by vibration in a manner to impart such tiny and rapid increments of intermittent progressive movement to the figurettes that they appear to travel uninterruptedly in a forward range of directions. In this manner figurettes may be made to advance without perceptible source of motivation and with seemingly smooth and continuous motion. The direction in which they tend to travel can be determined by the angle of forward, backward, sidewise or diagonal slant that is given to the flexible projections or pilose elements with respect to the facing direction of the figurette. On a given figurette all the pilose elements are preferably inclined in a common direction, and resilient.

Mechanical principles of figurette animation such as the foregoing are made use of broadly in the present invention by vibrating the floor surface of an imitative corral and/or railway car chassis and/or gangplank extending therebetween, without bodily vibrating the corral, car chassis or gangplank itself.

One object of the invention is to cause the figurettes to travel individually over selective paths within an enclosure, as well as out of and

2

back into such enclosure, by less easily detected means of motivation than have heretofore been proposed; also to cause the figurettes to progress automatically in a seemingly more natural manner as though they were actually walking smoothly about free from perceptible vibration, of bodily nature.

A more particular object is to predetermine courses of travel along which free and unattached figurettes shall be caused to advance automatically by vibration of the floor surface, and to provide means for effecting at will selective changes in such courses of travel.

A related object is to cause figurettes to ascend a ramp from a trackside corral located on a relatively low level and pass into an adjacent railroad car that is located at a relatively higher level, or to descend such ramp in a return path of travel from the railroad car back into the trackside corral.

A particular object is to transfer the mechanical function of motivating advancing figurettes from the vibrating floor surface of a trackside platform to the vibrating floor surface of a railway car chassis without necessitating any perceptible interruptions in the continuous travel of the figurettes.

A further object is to produce vibration of the floor surface in a toy structure by constituting such surface as a somewhat stiff, thin, friction affording sheet of material resting on an underlying support and free for edgewise vibratory movement in sliding relation to such support, as well as in sliding relation to figurette guiding stationary fence structure flanking the designed path of movement of the figurettes.

Another object is so to correlate two adjacent vibratory floor areas bordered and separated by fencing or partitions or guard rail structure that they resemble two neighboring corrals within either of which corrals toy figurettes representative of cattle can circulate while still other cattle figurettes are moving into or out of the neighboring corral.

A contributory object is to make use of adjacent gangways and separately adjustable adjacent gates located therein to determine whether the moving cattle figurettes shall be confined to one or both of the neighboring corrals or be caused to depart from or enter into either of such corrals.

These and further objects of the invention will appear in greater particular from the following description of a successful embodiment of the invention having reference to the accompanying drawings wherein various numbered sectional

views show the structure as observed in the direction of arrows bearing similar numbers.

In the drawings:

Fig. 1 is a plan view of a toy railway accessory embodying the present invention drawn in suitable actual size.

Fig. 2 is a fragmentary view taken in section on the planes 2-2 in Fig. 1.

Fig. 3 is a fragmentary view taken in section on the plane 3-3 in Fig. 1.

Fig. 4 is an elevation looking lengthwise of the track at Fig. 1.

Fig. 5 is a view taken mostly in section on the planes 5-5 in Fig. 1.

Fig. 6 is a fragmentary view taken in section on the plane 6-6 in Fig. 1.

Fig. 7 is a fragmentary view taken in section on the plane 7-7 in Fig. 1.

Fig. 8 is a fragmentary view drawn on an enlarged scale taken in section on the plane 8-8 in Fig. 1.

Fig. 9 shows in elevation one of the free moving figurettes drawn on an enlarged scale.

Figs. 10 and 11 are bottom plan views of the bases of differently colored figurettes which further differ from each other in the oblique direction at which the pilose nap of their base surface is directed.

In Fig. 1 a base plate 12 establishes fixed relationship between a stretch of toy track 13 and a somewhat elevated trackside platform 14 having an extension 15 on its side opposite the track. This extension carries a hollow toy building 16 representing a shed for cattle represented by the loose figurettes 10 and 11 that are free from random travel about the floor area of platform 14. The edges of platform 14 are bordered by fencing structure 17 lined at its base by a guard rail 18 affording generously rounded guiding corners for the floor area of the enclosure that is formed by the fencing structure. One stretch of the fencing structure lies alongside the toy track and contains a break 19 through which extends a gangplank 20 pivotally anchored to platform 14 at 21 so that the gangplank can be swung upward or downward to selected degrees of inclination to the horizontal. Any desired degree of inclination is maintained by frictional resistance occasioned by rubbing of the outsprung hinge tabs 23 of the gangplank against flanking tabs that depend from platform 14 as best shown in Fig. 7 at the sides of a break in platform 14 which accommodates the width of the gangplank. The gangplank has upstanding sides 22 for purpose of guiding the figurettes in their travel over the gangplank as will later appear.

A portion 24 of fence 17 adjoins the building 16 and extends inwardly of the fenced enclosure and fixedly stations two pairs of vertically spaced hinge brackets 25 on which are mounted respectively two like figurette guiding gates 26 and 27 by means of their lugs 28. Lugs 28 are so arranged on the gate with respect to hinge brackets 25 that the former are free to shift vertically relatively to the latter by sliding axially on the pivot pin 29. Upward movement of the gate is yieldingly resisted by the downwardly exerted tension of a spring coil 31 surrounding pin 29 and which is under compression between top hinge bracket 25 and bottom gate lug 28. This spring tension urges each gate downward so that a depending projection 32 on the bottom edge of each gate tends to seat yieldingly in either of two sockets 33 embossed in the sheet metal floor

surface of platform 14. These sockets of which there are two pairs enable either gate to remain fixed in either of two positions. In one of these positions each gate completes the figurette guiding fence enclosure surrounding its corral 70 or 71 while in the other position it opens a gangway leading from such corral to the foot of gangplank 20. As will later appear the position of either gate determines whether the animated figurettes shall merely circulate over a circuitous route confined to the interior of its corral, or whether the figurettes when they come to the gangway and find it open will leave the corral and proceed up the gangplank 20 toward and into a freight car 36 standing on track 13 with its open doorway 40 positioned to receive them.

The manner in which the figurettes are herein shown to be animated, or caused to advance automatically along selective paths of travel, involves rapid edgewise vibration of a loose covering sheet 37 for the floor of platform 14. This sheet is of suitable substance to be stiff enough to resist crumpling and may be very thin, light weight, stiff paper or cardboard, or plastic or the like, preferably having a top surface somewhat roughened, as for instance by embedded gritty or hairy content. It is cut to an outline shape sufficiently smaller than the fence bordered floor area of platform 14 to be free for short edgewise vibratory motion in sliding contact with the top surface of the platform. A resinous coated sheet mainly composed of glass fibers and known in the trade by the name of Glasson will prove to be satisfactory. An inclined integral tongue-like projection 38 of the vibrated sheet 37 rests on and extends the full length of the "walk" of gangplank 20 while an integral wide projecting tab 39 of the same sheet extends freely through a clearance space between platform 14 and the bottom edge of building 16 to the interior of the latter therewithin to derive its edgewise vibratory impelling motion.

The source of the vibrating motion within building 16 is an electromagnet energized, say, by 60 cycle alternating current of suitable voltage which may be derived from an ordinary toy transformer. The electromagnet consists of a solenoid winding 41 of insulated wire wound on a magnetically permeable spool core 42 having one of its ends firmly secured by the mounting screw 43 to an upstanding branch 44 of a support bracket 45 whose base flange 46 is removably secured to platform extension 15 by screws 47. The metal of support bracket 45 is also magnetically permeable and is so bent as to roof over solenoid 41. It then extends downward to serve as a resilient reed-like armature 48 that may be vibrated by the alternating current in the substantially closed magnetic field of solenoid core 42. It is permitted so to vibrate by proper thinness and spacing of the armature 48 with respect to the end of the spool core 42.

Armature 48 is operatively coupled to the tab 39 of vibratory sheet 37 through the instrumentality of its oppositely branching arms 50 each carrying fixedly on its outermost end a depending button 51 of semi-soft rubber that is secured by cement or in any other suitable way to the top surface of sheet tab 39 where the latter lies concealed within the toy building 16. The electromagnet thereby constitutes an invisible source of vibratory motion for the sheet 37 which mostly covers and slides reciprocatively on the floor area

of the neighboring corrals 70 and 71 as well as on the "walk" of gangplank 20.

The freight car, designated 36 as a whole, stands on track 13 and is equipped internally with an arcuate passageway directed lengthwise of the car and defined by laterally spaced curved partitions 57 and 58. Between these partitions there rests on the top surface of the chassis a vibratory floor covering sheet 59 consisting of a cut-out strip of material like that of sheet 37. The size and outline shape of sheet 59 is such as to permit edgewise reciprocative motion thereof lengthwise of the freight car between partitions 57 and 58. For imparting edgewise vibratory motion to the chassis covering sheet 59, the latter is provided with a-motivated extension tab 61 which may be an integral continuation of its own material and which is freely movable edgewise along a slot provided between the bottom of partition 57 and the car chassis 60, through which slot the tab 61 extends. This enables the car floor covering sheet 59 to be vibrated edgewise and lengthwise of the car by the armature 62 of the solenoid 63 whose spool core 68, like that of solenoid 41, is supported on a holding bracket 64 by means of a removable fastening screw 65. Bracket 64 is fastened by means of its base flange 66 to the car chassis 60 by holding screws 69. A rubber button 67, which may be like button 51, is fixedly carried on armature 62 and is firmly cemented to the top surface of tab 61.

The traveling response of the loose figurettes 10 and 11 is determined by the nature of the bottom surface of their respective bases 72 and 73. While each of said bases has permanently attached or cemented to it a swatch of springy, long-haired, pile fabric such as plush, this fabric is placed differently on the black figurettes 10 and brown figurettes 11, respectively, so that the downward pointing flexible pile slants transversely of the black figurettes in one diagonal direction, as indicated in Fig. 10, but slants transversely of the brown figurettes in the opposite diagonal direction, as indicated in Fig. 11. This gives the black figurettes 10 a tendency to move in the direction of arrow L in Fig. 11 whenever the surface on which the figurette rests is vibrated in either of the directions indicated by arrows X and Y in Fig. 11. But in response to floor vibration relative to the brown figurettes 11 in either of the directions indicated by arrows X and Y in Fig. 10, the brown figurettes will tend to move in the direction of arrow R in Fig. 10.

Thus vibration of the floor covering sheet 37, 38 in Fig. 1 in the directions of arrows X in Fig. 1 will cause the black figurettes 10 to tend to drift constantly toward the left and will cause the brown figurettes to tend to drift constantly toward the right as all the figurettes attempt to advance. Also vibration of the car chassis floor covering sheet 59 in the directions of arrows Y will cause the black and brown figurettes to drift in their different respective directions above explained. These opposite directional traveling tendencies of the black and brown figurettes cause the black figurettes to follow the guard rail 18 in a clockwise course of travel in corral 70 while the brown figurettes will follow the guard rail 18 in a counterclockwise course of travel in corral 71.

There remains to be described certain current conducting fittings for enabling the car carried vibrator magnet coil 63 to be electrically ener-

gized while the car is standing beside the stock yard corrals 70 and 71. Preferably this is accomplished by means of a third rail 75 stationed on and insulated from base plate 12 by bracket 79 and insulative spacer 80 and electrically supplied through an insulated lead wire 77. Current is collected from rail 75 by the car carried contact shoe 76 which is insulated from the car and connects electrically with one end of solenoid winding 63 by means of lead 78.

The other end of solenoid winding 63 is grounded to the car chassis whereby the current returns to source through the car wheels and one of the track rails 13. The length of third rail 75 is such that shoe 76 may contact therewith when either of the stock car doorways 40 or 40' registers with the end of gangplank 20. When doorway 40 so registers the figurettes will pass therethrough to or from the car over gangplank 20 the same as they do through car doorway 40. Conventional forms of slideable doors 49 and 49' may be provided to close and open their respective doorways 40 and 40'.

In operation, the figurettes will march in orderly courses of travel sliding against the guard rail 18 in both corrals unless diverted onto the gangplank and into the car by suitable setting of the gate 26 or 27. However, if the brown cattle that are shown already in the car in Fig. 1 were to be delivered back to corral 71 by first shifting the car along the track until doorway 40' registers with gangplank 20, then the brown cattle, seeking always to drift toward the right, would travel down the gangplank and upon entering corral 71 would find themselves launched into the open central space of the corral with temporary loss of ability to follow the guard rail 18. This might cause them to enter upon an irregular course of travel such as would bring them into contact with other cattle moving about in corral 71.

In this way the invention provides for random milling about of cattle figurettes of the same or differing colors in either corral and adds realism by simulating the characteristic performance of live cattle in a real stock yard.

Many other varieties of movement of the figurettes are predeterminable at will, such as by placing the rightwise drifting brown cattle in corral 70 or the leftwise drifting black cattle in corral 71 or by placing either kind of cattle confined to the car while facing in either of opposite directions. The cattle figures may be so placed and the toy so operated that the black cattle will continually circulate about in corral 70 blocked from escape therefrom by gate 26 while the brown cattle are leaving corral 71 and advancing one by one into the car. If turned about in the car or if car doorway 40' is moved into register with the gangplank and its door 49' then opened the cattle will return to the corral. Obviously these performances of the differently colored cattle can be interchanged between the two corrals or by closing both gates 26 and 27 cattle will circulate separately and simultaneously in the two corrals.

The appended claims are directed to and intended to cover all fair substitutes and equivalents for the herein disclosed particular shapes and arrangements of parts that come within the broadest interpretation of the claim language.

Claims directed to the toy railway car alone and in combination with figurettes appear in copending application divisional herefrom, Serial No. 309,490, filed September 13, 1952.

We claim:

1. An animated toy comprising in combination, a base having a vibratory floor surface clear of obstacles and substantially as wide as it is long, at least one loose figurette equipped to be impelled with a constant tendency to drift laterally as it is caused to advance over said floor surface by vibration of the latter, fencing structure nearly enclosing said floor surface slidably engageable by the side of said figurette toward which the latter tends to drift thereby to guide the figurette in a path of travel following the perimeter of said floor surface, a gangway in said guiding structure wide enough to permit escape of said figurette from said floor surface, and a gate spanning said gangway forming in one position a continuation of said guiding structure and completing the enclosure of said floor surface, said gate being shiftable at will to a position clearing said gangway and operative to guide said figurette in a path of escape through said gangway from said floor surface.

2. An animated toy comprising in combination, side-by-side vibratory floor surfaces, loose figurettes equipped to be impelled respectively about said floor surfaces by vibration of the latter, fencing structures nearly enclosing each of said floor surfaces slidably engageable by said figurettes respectively in a manner to direct a figurette on each of said floor surfaces in a path of travel following the perimeter of the floor surface, at least partially coincident gangways including respectively separate openings through said guiding structures permitting escape of a figurette from the floor surface enclosed thereby, and adjacent gates independently shiftable between predetermined absolute and relative positions, each of said gates in one of its said positions blocking a different one of said gangways and completing the enclosure of a different one of said floor surfaces and in the other of said positions clearing its gangway to permit escape of figurettes from each of said floor surfaces to a common point of departure therefrom.

3. An animated toy as defined in claim 2, in which both of the said vibratory floor surfaces are formed by a single thin sheet of stiff material, together with a vibrator connected to said sheet in a manner to impart thereto rectilinear edgewise reciprocative movement.

4. An animated toy as defined in claim 3 in which the said loose figurettes are equipped with pilose bases of two kinds, the pilose base of said figurettes which travel on one of the said floor surfaces having its pile disposed in one diagonal direction and the pilose base of said figurettes which travel on the other of said floor surfaces having its pile disposed in the opposite diagonal direction.

5. A toy railway accessory comprising in combination with a section of toy track, at least one loose figurette equipped to travel automatically in response to vibration of a surface on which it stands, a figurette animating station presenting a floor area beside said track with respect to which said figurette is free for random travel, a guard rail flanking said floor area slidably engageable by said figurette in a manner to influence the path of travel thereof, a miniature gangplank extending from said floor area in a direction toward said track, a toy railway car standing on said track at one end of said gangplank, a slidable sheet of material on which said figurette stands and travels, said sheet at least partially covering both said floor area and said gangplank

and being sufficiently stiff to resist crumpling when pushed and pulled in edgewise directions, and a vibrator connected to said sheet in a manner to cause rapid edgewise reciprocation thereof in directions toward and away from said track.

6. A toy railway accessory as defined in claim 5, in which the said gangplank and that portion of the said vibrated sheet of material covering the same are inclined in relation to the said floor area.

7. A toy railway accessory as defined in claim 5, in which the said gangplank and that portion of the said vibrated sheet of material covering the same are settable at selective angles of elevation relatively to the said floor area, together with means automatically operative to maintain said gangplank and sheet portion at a set angle of inclination.

8. A toy railway accessory as defined in claim 5, wherein the said vibrator includes a reciprocative actuator connected to the said floor covering sheet of material at spaced apart points, whereby said sheet is prevented from skewing in relation to said actuator.

9. A vibration animated toy comprising in combination, adjacent imitative corrals, separate fixed fencing structures nearly enclosing said corrals respectively, a vibratory floor in each of said corrals, at least partially coincident gangways affording exit from said corrals respectively through said fencing structures, and adjacent gates disposed to be shiftable between positions blocking and clearing said gangways respectively.

10. A vibration animated toy as defined in claim 9, in which the said gates are pivotally mounted to swing through overlapping paths of movement.

11. A vibration animated toy as defined in claim 9, in which the said gates are separately movable and thereby selectively positionable to block or clear either or both of the said gangways.

12. A vibration animated toy as defined in claim 9, together with a gangplank leading away from the point of coincidence of the said gangways.

13. A vibration animated toy as defined in claim 12, in which the said gates are pivotally mounted at one end on laterally spaced stationary pivots and have their opposite swingable ends disposed to be brought close together while directed toward the said gangplank.

14. A toy railway accessory comprising in combination with a section of toy track, at least one loose figurette equipped to travel automatically in response to vibration of a surface on which it stands, a figurette animating station presenting a floor area beside said track with respect to which said figurette is adapted to travel, a guide rail flanking said floor area slidably engageable by said figurette in a manner to determine a trackside path of travel thereof over said floor area, a miniature gangplank extending from said floor area in a direction toward said track, a toy railway car including a wheeled chassis standing on said track at one end of said gangplank, a first slidable sheet of material on the surface of which said figurette stands and travels, said sheet loosely carpeting both said floor area and said gangplank and being sufficiently stiff to resist crumpling when pushed and pulled in edgewise directions, a vibrator connected to said sheet in a manner to cause rapid edgewise reciprocation thereof in directions toward and away from

said track, a figurette guide rail on said chassis slidably engageable by said figurette in a manner to determine a path of travel thereof aboard said chassis, a second and separate slidable sheet of material on which said figurette is adapted to stand and travel loosely carpeting said path of travel aboard said chassis, and a vibrator connected to said separate sheet in a manner to cause rapid edgewise reciprocation thereof, said first and second sheets being in sufficient edge to edge proximity to enable the figurette temporarily to overlap and rest on both sheets simultaneously wherefore automatically to cause the figurette to be transferred from one to the other of said vibrating sheets.

15. A toy railway accessory comprising in combination with a section of toy track, at least one loose figurette equipped to travel automatically in response to vibration of a surface on which it stands, a figurette animating station presenting a floor area beside said track, a guide rail flanking said floor area slidably engageable by said figurette in a manner to determine a trackside pathway of travel therefor on said floor area, a toy railway car including a wheeled chassis standing on said track beside said floor area, separate relatively slidable thin stiff sheets of material on which said figurette can stand and travel loosely carpeting said floor area and said

chassis respectively, a guide rail on said chassis slidably engageable by said figurette in a manner to determine a pathway of travel therefor aboard said chassis, separate electro-magnetic vibrators connected respectively to said sheets in a manner to cause mechanically independent edgewise reciprocation thereof for propelling said figurette, said sheets being edgewise adjacent at a transfer place and said pathways being co-directional at said transfer place whereby said figurette can be propelled toward and transferred to one of said pathways automatically from the other of said pathways.

16. A toy railway accessory as defined in claim 15 in which at least one of the said pathways is sloping.
